UNITED STATES PATENT OFFICE.

GRANT PENDLETON AND McCLELLAN C. PENDLETON, OF McCOMB, OHIO.

CORN-HARVESTER.

SPECIFICATION forming part of Letters Patent No. 469,174, dated February 16, 1892.

Application filed June 16, 1891. Serial No. 396,489. (No model.)

To all whom it may concern:

Be it known that we, GRANT PENDLETON and McCLELLAN C. PENDLETON, both of McComb, in the county of Hancock and State of Ohio, have invented a new and Improved 5 Corn-Harvester, of which the following is a full, clear, and exact description.

Our invention relates to improvements in corn-harvesters; and the object of our invention is to produce a simple and efficient machine which will cut two rows of corn-fodder at a time and will deliver the same in bundles at the sides of the machine.

To this end our invention consists in certain 15 features of construction and combinations of parts, which will be hereinafter described and claimed.

Reference is to be had to the accompanying drawings, forming a part of this specification, 20 in which similar figures of reference indicate corresponding parts in all the views.

Figure 1 is a side elevation of the machine embodying our invention. Fig. 2 is a plan view of the same. Fig. 3 is an inverted plan 25 view. Fig. 4 is a cross-section on the line 4-4 in Figs. 1 and 2. Fig. 5 is an enlarged detail view of the treadle mechanism for operating the side leaves, and Fig. 6 is an enlarged detail view of the lever mechanism for operating the clutch.

The machine is provided with a main frame 10, which is widened at its rear end and is connected with the side pieces 11 of the table on which the fodder is delivered, and these 35 side pieces support the cross-bars 12, which are united at their outer ends by rods 13, and the cross-bars also support a central vertical frame 14, which divides the delivery-table into two parts. This frame 14 is provided 40 near the bottom and on each side with an inclined shield 15, which causes the fodder to slide toward the sides of the machine, and the frame is steadied by a brace 16, which connects it with the frame 10, and on this brace 45 is a seat 17, although the seat may be supported in any convenient way. On the outer sides of the table are the swinging leaves 18, which are pivoted to the rods 13, and which have supporting-ribs 19 on their under sides, 50 the said ribs being mounted upon the rods 13 and having their inner free ends adapted to

rest upon the side pieces 11 of the table. The center ribs 19 of the leaves have depending links 20, which at their lower ends are secured to connecting-rods 20^a, and these extend inwardly beneath the machine and are secured at their inner ends to opposite ends of a double crank 21, which is secured to a vertical shaft 22, the latter terminating at its upper end in a crank 23, and a connecting-rod 24 extends forward from the crank and is secured at its forward end to a crank 25 on a shaft 26, which is supported upon a portion of the frame 10, and extending upward from this shaft is a treadle-lever 27, which is arranged so that it may be easily reached from the seat 17, and by pressing downward upon the treadle-lever with the foot the crank 22 60 will swing so as to draw inward the connecting-rods 20^a, and the leaves 18 will swing upward, as indicated by dotted lines in Fig. 4, thus causing the fodder which is upon them to be thrown off on each side of the machine.

The machine is mounted on wheels 28 and 29, there being two of the wheels 28 on the 75 rear end of the machine and one wheel 29 on the front end, the wheels being severally mounted in slotted boxes 30, which are adjusted vertically by means of the bolts 31, and the frame may be therefore brought to 80 any desired height. The wheel 29 is larger than the rear wheels and serves as a driving-wheel. It is secured to an axle 32 and is provided on one side with a sprocket-wheel 33, which connects by means of a chain 34 with 85 a sprocket-wheel 35 on a clutch 36, which clutch is held to slide on a transverse shaft 37, mounted in the frame 10 in the rear of the axle 32. The clutch is adapted to engage the teeth on the hub of one of the gear-wheels 38, 90 which gear-wheels are secured to the shaft 37 near opposite ends thereof, and extending forward from the clutch is a rod 37^a, the front end of which is pivoted on the frame 10 and terminates in a laterally-extending crank 37^b, 95 as shown in Fig. 2, which connects at its free end by means of a link 38^a with a lever 39, the lever being pivoted to a support 40 on the main frame 10 and extending to a point where it may be conveniently reached from the seat, 100 so that by moving the lever the clutch may be made to slide on the shaft and to engage

the gear-wheel or to be moved away from the same. Each gear-wheel 38 meshes with a gear-wheel 41, which turns horizontally on a bolt 42, the said bolt being secured to the under 5 side of the main frame, and each bolt 42 carries a rotary cutter 43, and the cutters, being pivoted on opposite sides of the frame, will thus be adapted to cut simultaneously two rows of fodder.

10 The following device is used for tightening the driving-chain 34, so that the parts will operate without any lost motion. A common segmental rack 44 is secured to the upper side of the frame 10, and pivoted opposite the rack 15 is a lever 45, having the usual catch thereon, which engages the rack, and this lever terminates at its lower end in a laterally-extending crank 46, which carries a roller 47, the said roller extending beneath the chain 34, and by 20 moving the lever the roller may be forced up against the chain, thus tightening the same. At the extreme front end of the machine is a common form of draft-bar 48, to which a pair of shafts or other hauling device may be attached.

25 The operation of the machine is as follows: It is drawn lengthwise of two rows of corn-fodder, so that the cutters 43 will come opposite the stalks, and the clutch 36 is thrown by 30 the lever mechanism above described so that the gear-wheels will be turned and the cutters revolved, and consequently the cutters will sever the stalks as fast as they come in contact with them. As the stalks are cut they

fall backward upon the shields 15, and are 35 thereby made to slide upon the leaves 18, and when a sufficient number of stalks have accumulated the driver presses downward on the treadle 27, thus swinging the leaves upward and outward in the manner described 40 and depositing the stalks at the sides of the machine.

Having thus described our invention, we claim as new and desire to secure by Letters Patent—

45 A corn-harvester comprising the wheeled frame 10, having the transverse beams 12, central longitudinal oppositely-inclined shields 15 15 thereon, the rods 13, connecting the outer ends of the beams, the outward and upward 50 swinging leaves 18, lying horizontally on the frame alongside of the lower edges of the shields and having transverse cleats or ribs 19 on their lower sides, pivoting near their outer ends on said rods and having depending arms 20, the rocking lever 21, connected at its ends with the said arms and having an operating-arm 23, the rod 24, connected with said arm, the operating-lever connected with said arm 23, the horizontal rotary cutters 43, 55 and means for operating them, substantially as set forth.

GRANT PENDLETON.
McCLELLAN C. PENDLETON.
